(57) **CLAIM**

The ornamental design for a shooting target holder, as shown and described.

DESCRIPTION

FIG. 1— $\frac{3}{4}$ front perspective view of the shooting target holder;

FIG. 2—front elevation view of the shooting target holder-enlarged;

FIG. 3—right side elevation view of the shooting target holder-enlarged;

FIG. 4—in use $\frac{3}{4}$ front perspective of the view shooting target holder; and,

FIG. 5—alternative configuration: in use $\frac{3}{4}$ rear perspective view of the shooting target holder.

The broken line showing of portions of the shooting target holder shown in FIGS. 1 through 5 do not form a part of the claimed design. The broken lines showing of a clay pigeon in FIG. 5 is for the purpose of illustrating environment and does not form a part of the claimed design.
